UNITED STATES PATENT OFFICE.

LUDWIG GROTE, OF TOTTENHAM, LONDON, ENGLAND.

BURNER OF THE INJECTOR TYPE.

Application filed August 15, 1922. Serial No. 581,926.

To all whom it may concern:

Be it known that I, LUDWIG GROTE, engineer, a citizen of the German Republic, residing at 177 Mount Pleasant Road, Tottenham, London, England, have invented certain new and useful Improvements in or Relating to Burners of the Injector Types, of which the following is a specification.

Heretofore a liquid hydrocarbon burner of the injector type has been proposed with a central longitudinal passage or barrel extending from end to end of the burner and having at its rear end a compressed air inlet in alignment with the axis of said barrel and adapted to deliver said air under pressure direct through said barrel and having a circular enlargement near the rear end of said barrel and in advance of said compressed air inlet with an inlet or inlets for admitting air at atmospheric pressure or gas or steam to said enlargement, and having an inlet or inlets for delivering liquid hydrocarbons laterally into said barrel at a point well in advance of said enlargement and also having an annular steam jacket adapted to deliver through the outlet end of the burner a ring of steam around the jet of mingled air and liquid hydrocarbons as said jet leaves the outlet end of the barrel.

Now the present invention relates to burners or burner apparatus of the aforesaid type; but instead of delivering the supply of liquid hydrocarbons or it may be gas (all of which fuels will hereinafter be referred to as the liquid fuel) laterally into the barrel of the apparatus between the enlargement and the outlet end of the barrel as heretofore, such liquid fuel supply according to the present invention is delivered into the said enlargement, namely according to one arrangement said liquid fuel supply is delivered laterally into the said enlargement adjoining the compressed air inlet or according to another arrangement is delivered co-axially with the compressed air or steam into said enlargement.

Furthermore I provide means to permit air from the outside atmosphere to be drawn into said enlargement there to mingle with

the fuel and with the air delivered through the compressed air inlet; and in one construction according to this invention I provide means to admit air from the outside atmosphere into the barrel of the burner or burner apparatus as hereinafter described, which barrel is made conical or tapering gradually and regularly (symmetrically from the aforesaid enlargement to the nozzle or outlet from the burner.

Furthermore an annular chamber or chambers (of any suitable character) is or are provided around the barrel towards the nozzle or outlet end of the burner from which air (under pressure or not) or steam is or are delivered through the said outlet end of the burner either through a ring of small holes or through a circular slot located concentrically around the bore; and according to the present invention the said ring of holes or circular slot is arranged to deliver said annular ring of air or steam through the outlet end of the burner at an acute angle to the longitudinal axis of the barrel of the burner so as to cause said ring of air or steam to be directed forcibly at a point close to the exit end of said barrel into the mixture of liquid fuel and air emerging from the barrel outlet or nozzle.

In one construction according to this invention I provide two such annular chambers concentric with the bore of the burner; air or steam under pressure is delivered to one such chamber and thence to the issuing fuel and air stream, the injection action thus established causing air to be drawn through suitable apertures into the second annular chamber and thence to the fuel and air stream.

Furthermore in the first above described construction, according to the present invention, the means for admitting air from the outside atmosphere to the barrel between the enlargement towards the rear end of the barrel and the nozzle of the latter consist of forwardly sloping apertures (advantageously conical or tapering) formed through the wall of the barrel and inclined towards the outlet end of said barrel.

Similarly inclined openings for admitting air from the outside atmosphere into the enlargement may be formed through the wall of the latter and advantageously in the rear end wall of the enlargement.

If desired, steam may be delivered (with the compressed air) through the aforesaid compressed air inlet at the rear end of the burner.

- 10 The liquid fuel is delivered into the aforesaid enlargement (at the rear end of the burner) either through the top of said enlargement and thence falls into and mingle with the incoming jet of air under pressure; or said liquid fuel may be delivered into said enlargement in any other suitable manner and by any other suitable means, e. g. axially with the incoming jet of air under pressure through an annular aperture surrounding the nozzle through which the said air or steam is projected.

15 The burner is provided with a lug or support on the underside thereof by which same can be mounted (in the known manner) so as to be capable of tilting or otherwise.

20 One form of burner constructed according to my present invention is illustrated in Figs. 1 to 7 of the accompanying drawings, in which:—

25 Fig. 1 is a plan view showing the position of the liquid fuel inlet to the circular enlargement and the air or steam inlet to the annular chamber in the barrel towards the outlet end of the burner.

30 Fig. 2 is a central vertical sectional view on the line 2—2 Fig. 1.

35 Fig. 3 is a front end view looking in the direction of the arrow *x* Fig. 1.

40 Fig. 4 is a cross-sectional view on line 4—4 Fig. 2 looking in the direction of the arrow *y*.

45 Fig. 5 is a cross-sectional view on line 5—5 Fig. 2 looking in the direction of the arrow *z*.

50 Fig. 6 is a central longitudinal section of the injector nozzle and

55 Fig. 7 a front end view of the same.

60 Figs. 8 to 17 show an alternative construction.

Fig. 8 is a view in side elevation of this construction of burner.

Fig. 9 is an end view of Fig. 8 looking in the direction of the arrow *a*.

Fig. 10 is a front end view of Fig. 8 looking in the direction of the arrow *b*.

Fig. 11 is a vertical longitudinal sectional view.

Fig. 12 is a transverse sectional view on line *c*—*c* Fig. 8.

65 Fig. 13 is a central longitudinal sectional view of the barrel portion of a burner constructed according to this invention.

70 Fig. 14 is a similar longitudinal sectional view of the air or steam injector portion.

Fig. 15 is a similar view of the air or steam injector nozzle.

Fig. 16 is a similar view of an inner sleeve adapted to be screwed over the barrel portion shown in Fig. 13; and

Fig. 17 is a similar view of an outer cylindrical sleeve adapted to be screwed over the inner sleeve shown in Fig. 16.

75 As illustrated in Figs. 1 to 7 of these drawings one form of burner constructed according to this invention comprises two principal parts viz, the main part or barrel 20 and the fore-part or cylindrical sleeve 21.

The said main part 20 is provided with a boss 22 internally screw-threaded for attaching thereto the liquid fuel supply pipe. An aperture 23 admits the liquid fuel to the circular chamber 24 to which also air is drawn in through a plurality of tapered apertures 25 by the action of the air or steam injector 26 which is screwed into a boss 27 on the main part 20.

80 Air is also admitted to the barrel portion of the main part A through inclined and tapered apertures 28.

85 The fore-part or cylindrical sleeve 21 is adapted to be tightly and rigidly screwed to the front portion of the main part 20 and is provided with a downwardly projecting extension 29 by which the burner can be attached to or mounted adjustably or otherwise on any suitable support.

90 A boss 30 is provided on the cylindrical sleeve 21 and is internally screw-threaded to receive means for supplying air or steam under pressure, to the annular chamber 31 extending completely around the nozzle of the burner whence this air or steam is directed at an acute angle to the longitudinal axis of the barrel into the ignited fuel and air stream issuing from the bore of the burner, and is thereby intimately mixed therewith.

95 This said converging stream of air or steam may be directed from a ring of inclined apertures or from an inwardly inclined annular orifice 32.

100 As shown in Figs. 8 to 17 of the accompanying drawings;—the air or steam injector comprises two parts viz, (a) an outer casing 33 which is adapted to be screwed into the enlargement 34 of the barrel portion 35, the bore of this outer casing 33 tapers slightly in the direction of its attachment to the barrel 35 and (b) a removable nozzle 36 having a tapering bore and provided with a circular boss or flange 37 adapted to fit within the bore of the casing 33.

115 The main portion of this removable and interchangeable nozzle 36 being of smaller diameter than the circular boss or flange 37 thus leaves round said main portion between the outer surface thereof and the inner

surface of the outer casing 33 an annular space 38 (Fig. 11). The bosses or flanges 39 and 40 are provided on this outer casing 33 and are internally screw-threaded to permit the attachment thereto of the fuel inlet pipes leading to any suitable source.

Tapered apertures 39^a and 40^a form separate liquid fuel inlets to the annular chamber 38 and said liquid fuel is drawn by the injector action of the air or steam through the nozzle 36 into the circular enlargement 34 through the annular opening 41 which is the end of the annular chamber 38 formed between the outer surface of the nozzle 36 and the inner surface of the outer casing 33.

Apertures 42 are provided in the rear end of the enlargement 34 for the purpose of admitting an extra supply of air under the injector action of the incoming air or steam under pressure.

To provide for the intimate mixing of a further supply of air or steam to the mixed fuel and air issuing from the burner I provide a cylindrical sleeve 43 adapted to be screwed over the barrel portion 35 against a flange 35^a formed thereon.

This sleeve 43 is so formed and proportioned as to leave between its inner surface and the outer surface of the barrel 35 an annular chamber 44 terminating at the nose end thereof in an inwardly inclined annular slot or aperture 44^a the outer sleeve formed similarly to the inner sleeve 43 is screwed on over said sleeve 43 and is so formed and proportioned as to leave an annular chamber 46 similar to the chamber 44 (and correspondingly inwardly inclined at the forward end 46^a thereof) between its inner surface and the outer surface of the inner sleeve 43.

An aperture 47 is provided in the sleeve 43 and a boss 48 is formed on the sleeve 45 having a passage therethrough and provided with screw-threads for attaching thereto a pipe or conduit from any suitable source of air or steam under pressure.

A tapering nozzle 50 connects the inlet pipe for the air or steam under pressure to the annular chamber 44.

This nozzle 50 is detachable and is placed in position after the sleeves 43 and 45 are screwed into position as before described, with the aperture 47 and the boss 48 registering.

The aperture 51 and passages 52 are formed in the screwed flange of the inner sleeve 43 for the purpose of admitting to the annular chamber 46 air from the atmosphere.

The action of this part of the burner is as follows:—

Air or steam is admitted to the inner annular chamber 44 through the aperture 47 and is forced out through the inwardly inclined annular slot or aperture 44^a into the

mixed fuel and air stream issuing from the bore.

The injector action of this air or steam under pressure causes the additional supply of air to be drawn in through the apertures 51 and passages 52 to the outer annular chamber 46 and this additional air is drawn through the inwardly inclined slot or aperture 46^a.

Thus the two streams of air or steam are so directed as to converge all round on and become intimately mixed with the main fuel and air stream issuing from the bore.

Instead of employing liquid hydrocarbons as the fuel for this burner gas may be used as the fuel in this burner or burner apparatus according to this invention and such burner being designed and adapted to burn either gas or liquid hydrocarbons as the fuel; e. g. gas from the ordinary town gas supply may be used in this burner or any other suitable combustible gas.

What I claim is:—

1. A liquid hydrocarbon burner of the injector type comprising a barrel whereof the major portion of the bore increases regularly in cross sectional area towards the nose end of said bore, said barrel having a circular enlargement of said bore at the rear end of said bore, an injector nozzle for injecting gas under pressure arranged co-axially with the bore in the rear wall of said enlargement, means to admit liquid hydrocarbons directly into said enlargement, and means to direct an auxiliary supply of gas under pressure in sharply converging streams on to the main stream of fuel mixture issuing from the nose of the burner, substantially as described.

2. A liquid hydrocarbon burner of the injector type comprising a barrel whereof the major portion of the bore increases regularly in cross sectional area towards the nose end of said bore, said barrel having a circular enlargement of said bore at the rear end of said bore, an injector nozzle for injecting gas under pressure arranged co-axially with the bore in the rear wall of said enlargement, an annular chamber concentric with and surrounding said injector nozzle for the supply through said annular chamber of liquid hydrocarbons into said enlargement at the rear end of the bore of the burner, and means to direct an auxiliary supply of gas under pressure in sharply converging streams on to the main stream of fuel mixture issuing from the nose of the burner, substantially as described.

3. A liquid burner of the injector type comprising a barrel having a conical bore, said barrel having an enlargement of the bore at the small end of the latter, an injector nozzle co-axial with said bore, and arranged to deliver gas under pressure into the rear of said enlargement, means to ad-

mit fuel directly to said enlargement, two concentric cylindrical sleeves arranged on the fore-part of the burner and forming two concentric annular chambers each having the outlet therefrom inclined inwardly at an acute angle to the bore of the burner,

an inlet to one of said annular chambers for supplying thereto gas under pressure, and an inlet to the other said annular chamber for admitting air from the atmosphere.

LUDWIG GROTE.
